WRIST WATCH

André Le Marquand, Bulle, Switzerland, assignor to
Catena S.A., Fribourg, Switzerland

Filed Apr. 5, 1973, Ser. No. 348,253

Claims priority, application Switzerland Oct. 13, 1972

Term of patent 14 years

Int. Cl. D10—01

U.S. Cl. D10—39

FIG. 1

FIG. 2

FIG. 3

FIG. 1 is a right front perspective view of a wrist watch showing my new design;

FIG. 2 is a top front perspective view thereof; and
FIG. 3 is a top rear perspective view thereof.

The left side of the wrist watch has the same appearance as the right side but without the outstanding tubular stem. The bottom surface is flat and planar.

I claim:

The ornamental design for a wrist watch, as shown and described.
